UNITED STATES PATENT OFFICE.

FRANK HOWARD REXTREW, OF HAMMOND, INDIANA, ASSIGNOR TO ROY E. GREEN,
OF WHITING, INDIANA.

EYE-SHIELD.

1,188,679.

Specification of Letters Patent. Patented June 27, 1916.

Application filed May 8, 1914. Serial No. 837,113.

To all whom it may concern:

Be it known that I, FRANK HOWARD REXTREW, a citizen of the United States, residing in the city of Hammond, county of 5 Lake, and State of Indiana, have invented certain new and useful Improvements in Eye-Shields, of which the following is a specification.

My invention relates to shields adapted to 10 protect the eyes of the wearer from inclement elements such as wind, cold and dust.

The invention has for its principal objects the provision of an eye shield which is easy and quick of application, certainty 15 of retention in position for use, durable and effective in service, and comfortable to the wearer thereof.

A particular object is the provision of a shield which will be free from objectionable 20 breakage due to folding, and at the same time to provide a shield which may be folded compactly so as to occupy small space in the wearer's pocket.

Further objects are to provide a shield 25 which is neat in appearance and in some forms substantially invisible, and which will automatically conform to the ordinary configuration of the human face about the eyes.

An important specific object is the provision of holding means for such a shield 30 which themselves occupy small space and are always ready for application, requiring no adjustment, and which effectively secure the shield upon the face firmly and yet com- 35 fortably.

Still other objects will appear hereinafter.

In the accompanying drawings, which form a part of this specification, I have illustrated a preferred embodiment of these 40 improvements and means for forming the shield element.

In Figure 1 the shield is shown as applied in use; Fig. 2 is a side view of the shield complete; Fig. 3 is a face view of the middle 45 and end sections of the shield proper before being joined together; Fig. 4 is a perspective of a forming device or templet with a shield in process of formation therein; and Fig. 5 is a fragmentary sectional view of one 50 end of the templet and shield shown in Fig. 4, as on the line 5—5 thereof.

The shield proper is formed preferably of thin and flexible material. For the purpose 55 of this description this material may be called transparent or substantially trans-

parent, which is intended to denote broadly the property of permitting objects to be viewed therethrough. The material preferably employed by me is what is known as artificial ivory, celluloid, pyrolin, etc., and is made with various tints or colors, such as 60 amber and green, and is also furnished clear, that is, untinted. The shield proper comprises preferably a substantially rectangular intermediate or middle section 10 having a 65 length suitable to the ordinary width of the face across the eyes, and two end sections 11, one thereof being secured at each end of the middle section 10. A recess or opening 12 is provided in one side of the section 10 in- 70 termediate its ends to accommodate the nose of the wearer, thereby permitting the section 10 to fit suitably upon the face about the nose and under the eyes.

The ends of the section 10 are preferably 75 cut straight across, that is, substantially at right angles with the sides, and the end sections 11 are cut preferably so that substantially the apex of a triangle (as A, 14, B Fig. 3) is formed by that portion thereof which 80 is adapted to overlap and be secured to the end of the middle section. It will be noted that the end or apex portion 14 of the end section is slightly rounded which is advantageous in preserving a rounded contour to 85 the front of the shield at the ends thereof when in use and in forming a tight joint on easy lines at the portion 14. The portion of the end sections 11 substantially opposite to the triangular portion just described (D, 90 Fig. 3) is preferably rounded as shown, adapting the same to fit nicely at the side of the face around the eyes. Whatever shape 95 be selected for the sections, the adjoining edge portions of the end and middle sections should be so formed that when the shield is in position on a wearer's face, the shield is concavo-convex at the two end portions thereof.

In making my improved eye shield the former or templet 15 may suitably be employed, consisting of a piece of light sheet metal somewhat dished and boat-shaped as shown in Fig. 5 or given any other suitable shape as may be desired. The middle section 10 of the shield is preferably just long enough to fit between the substantially right-angularly positioned end walls 15^a of the templet. The middle section 10 being thus positioned in the templet, a small quantity of 110

transparent cement C is preferably applied at the corner portions 10^a of the section 10, whereupon an end section 11 is applied with the apex 14 to the end of the section 10 as shown in Fig. 5 and against an end wall 15^a, the triangular shaped edge portions 13 thereof being caused to overlap similar end portions 13^a of the section 10. A pressure with the thumbs upon the cemented portions causes them to adhere, whereupon the other end section may be similarly applied.

Heretofore in somewhat similar eye shades provision has been made for maintaining the main body portion away from the wearer's eyes by notching the ends of the body portion and securing together the portions of the device adjacent to the notch in overlapped relation, thus causing a raised portion in the body portion having its apex at the end of the notch. Devices of this kind are folded so as suitably to be carried in a pocket, one end being first folded down, the device being then folded in the middle, the other end portion then being bent down around the first mentioned end portion. Such bending in hitherto suggested devices causes the material to break beginning at the apex or end of the notch, and because of the stiffness of the end portions, owing to the notch arrangement, it is not possible to fold the parts closely together without at once ruining the structure. In the present device these objections are overcome, for there is no breaking strain whatever upon the apex, as 16, Fig. 2, when the end section is folded down and from this apex to the sides there is a double thickness of the material, greatly strengthening the device at what would normally be the breaking line. Furthermore, owing to the fact that the apex portion 14 is loose with respect to the middle section 10 this portion 14 moves thereupon in folding and assumes a more flat or parallel relation thereto. Thus the portion which would normally break is already cut through, and yet when the device is in position for use there is a neat and tight joint at the corner or apex 16.

It is a property of the device that when the same is secured upon the face in the manner shown in Fig. 1 the upper, lower and end edges conform to the shape of the wearer's face about the eyes within relatively wide limits. Should it be desired to vary the shape of any portion, as for instance the part accommodating the nose, the same may readily be done with a pair of scissors or a knife.

For purposes of ventilation I preferably punch a plurality of holes 17 in each end section 11, and in this connection it is pointed out that by reason of the substantially right-angular relation of the end and middle sections a strong current of air within the shield when in use is avoided, the

heavy current of air, as in motoring, passing by these openings and only small deflected and broken currents entering between the shield and the eyes.

An important feature of my invention comprises the means shown for securing the shield proper upon the face. Hitherto, so far as I am aware, the only device suggested for such a purpose consists of a cord or band passing entirely around the head and secured to the shield. Such a cord or band frequently requires adjustment and at best does not hold the shield against up and down movement on the face, particularly the upward movement as when struck by a heavy current of air, nor tightly or comfortably thereon. To overcome these objections I have provided loops 20, secured to the end sections 11, formed of light elastic fabric or cord, and adapted to pass around the wearer's ears. Such elastic loops, having considerable stretching properties, are found suitable in practically all instances of use and require no adjustment, and as they draw upon the shield simultaneously in several directions, the shield is held upon the face securely and comfortably and without danger of displacement by the wind or other agency hitherto found objectionable in the direction specified. A particular advantage of this provision is found when the usual eye glasses or spectacles are worn between the eyes and the shield.

Various changes may be made in the construction shown and described, as in varying the angles on which both the middle and the end sections are cut, means for holding the device upon the face, in the materials employed, etc., all within the spirit of the invention herein set forth. Reference should be had, therefore, to the appended claims to determine its scope, and all such changes are contemplated by me as fall within the scope of these claims.

I claim:

1. An eye shield comprising a middle section of thin and flexible substantially transparent material, a separate and independent end section joined to said middle section at each end thereof and foldable upon said middle section, said end sections being so formed and joined to said middle section that the shield is concavo-convex at the end portions and said middle section is maintained away from the eyes of the wearer when the device is in proper position for use upon the face, the respective lines of folding passing between contiguous edge portions of said end and middle sections.

2. An eye shield of thin and flexible substantially transparent material and having a shape which substantially conforms to the wearer's face about the eyes, said shield comprising a middle section and two separate and independent end sections, said end and mid-

- dle sections being so shaped and joined together as to form a shield having a front wall and two end walls adapted to contact the wearers face, said end walls being foldable upon said middle wall, the folding lines passing between contiguous edge portions of said end and middle walls respectively, and means for holding the shield upon the face.
- 10 3. An eye shield comprising a middle section of flexible substantially transparent material and two end sections, said end and middle sections overlapping at corner portions thereof respectively and secured together at the overlapped portions, said end sections respectively being free of said middle section at a place substantially medial of the places where respectively secured together, said end sections forming end walls
- 15 20 25 30 35 adapted to maintain said middle section away from the wearer's eyes when in use and be foldable upon said middle section when not in use, the folding lines passing through said places where the middle and end sections are free of each other, and means for holding said shield upon the face of a wearer.
4. An eye shield comprising a middle section of thin and flexible material through which the wearer thereof can see, said middle section having a nose opening or recess in a side thereof, a section of thin and flexible material secured to said middle section at each end thereof, said middle section and said end sections respectively being so formed at the joined portions thereof respectively that when the end sections and the middle section are secured together with a
- small portion of each overlapping the other, the middle section is bowed outwardly and the end sections are at such an angle to the middle section that an interior pocket is formed at each end of said middle section, said end sections being substantially free of said middle section at the apex or angle of the pockets respectively, said end sections being adapted to fold upon said middle section with the folding lines passing through the angle or apex of said pockets, and means for holding the shield on the face of the wearer.
5. In an eye shield, the combination of a shield proper and means for securing the same upon the face of a wearer for use, said means comprising a pair of flexible elastic loops, one thereof being secured at each end of said shield proper, said loops being adapted to pass around the ears respectively of the wearer.
6. An eye shield comprising a middle section of thin and flexible material through which the wearer may see, and separate and independent end sections of thin and flexible material suitably attached to said middle section and foldable thereupon, the adjoining edge portions of said end and middle sections respectively being so formed that when the shield is in normal use on a wearer's face the shield is concavo-convex at the two end portions thereof, and said middle section is maintained away from the eyes of the wearer.
